UNITED STATES PATENT OFFICE.

HENRY L. ROTHSCHILD, OF SAN FRANCISCO, CALIFORNIA, ASSIGNOR TO
ROTHSCHILD & HADENFELDT, OF SAN FRANCISCO, CALIFORNIA, A
CORPORATION OF CALIFORNIA.

DESIGN FOR A MATCH-SAFE OR SIMILAR ARTICLE.

SPECIFICATION forming part of Design No. 36,911, dated May 10, 1904.

Application filed March 30, 1904. Serial No. 200,802. Term of patent 7 years.

To all whom it may concern:

Be it known that I, HENRY L. ROTHSCHILD, a citizen of the United States, residing in the city and county of San Francisco, State of California, have invented a new, original, and ornamental Design for a Match-Safe or Similar Article, of which the following is a specification, reference being had to the drawings accompanying the original petition and specification and forming a part thereof.

Figure 1 is a plan view of the obverse side,

showing my new design. Fig. 2 is a plan view of the reverse side, showing the new design for the same.

What I claim as new, and desire to secure 15 by Letters Patent, is—

The ornamental design for a match-safe or similar article, as shown.

HENRY L. ROTHSCHILD.
